DETAILED DESCRIPTION

The solutions of the present disclosure will be described below in conjunction with the accompanying drawings and specific embodiments from which these solutions will be apparent to those skilled in the art. If not in collision, the following embodiments and the features thereof may be combined with each other.

In the present disclosure, the working principle of a power plug and a power socket working together with each other is as follows: when an electrical device is connected to AC power and is in a normal working state, a set of DC terminals provided on the power plug and the power socket are non-conductive between each other, and the AC power can ensure normal running of the electrical device; when the connected AC power is cut off, the set of DC terminals are conductive between each other, and DC power connected from outside of the electrical device supplies power to the electrical device, thereby ensuring that the electrical device can still run normally after the AC power is cut off.

Embodiment I

As illustrated in FIGS. 1 to 8, the present embodiment provides a power plug including a body 101, at least two AC plug terminals fixed inside the body 101, and two DC plug terminals fixed inside the body 101. Two AC plug terminals and two DC plug terminals are fixedly connected to the second body 107. Each of the AC plug terminals and each of the DC plug terminals are respectively connected to separate connecting wires penetrating out of the first body 106. The connecting wires penetrating out of the first body 106 are cladded into one conducting wire 109.

An end of the conducting wire 109 far from the AC plug terminals and the DC plug terminals is connected to an electrical device.

Two mounting holes 1071 are provided inside the second body 107. One AC plug terminal may be disposed in each of the mounting holes 1071. The AC plug terminals may include the L plug terminal 102 and the N plug terminal 103. Two opposite slots 1073 are disposed on side walls of each mounting hole 1071. The first flexible claw 1021 and the second flexible claw 1022 are flexibly joined to and pressed against with the slots 1073 so as to fix the L plug terminal 102 to the mounting hole 1071 so that the L plug terminal 102 does not slide out of the mounting hole 1071 easily. The N terminal 103 is also provided with a first flexible claw 1031 and a second flexible claw 1032 opposite to each other so that the N terminal 103 is tightly fixed into the mounting hole 1071. Material of the flexible claws may be phosphor copper. The phosphor copper is flexible and thus can make the flexible claws joined to and pressed against the slots 1073.

Moreover, at least three mounting holes 1071 may further be disposed inside the second body 107. A corresponding number of AC plug terminals may be disposed inside the mounting holes 1071. A second protrusion 1051 is provided on the negative DC plug terminal 105. By respectively clamping the first protrusion 1041 and the second protrusion 1051 to two mounting notches 1074, two DC plug terminals are respectively fixed inside two mounting slots 1072. The DC plug terminals may adopt gold-plated designs to improve electrical conductivity, corrosion resistance and abrasive resistance of the DC plug terminals.

The number of the mounting holes 1071 and the number 55 of the mounting slots 1072 in mounting structures are not limited, and are sum up to the number of the terminals. The mounting holes 1071 and the mounting slots 1072 may also be disposed in a length direction of the body 101. Moreover, the mounting structures may also be disposed on the first body 106. The mounting structures may include stack mounting of the first body 106 and the second body 107.

An end of the L plug terminal 102, the N plug terminal 103, the positive DC plug terminal 104 and the negative DC plug terminal 105 closer to connecting wire is provided with a wire connecting portion. A wire connecting portion of the L plug terminal 102 is connected to an L wire (live wire) of the electrical device. A wire connecting portion of the N plug

terminal 103 is connected to an N wire (null line) of the electrical device. A wire connecting portion of the positive DC plug terminal 104 is connected to a DC positive wire of the electrical device. A wire connecting portion of the negative DC plug terminal 105 is connected to a DC negative wire of the electrical device. Material of the wire connecting portions of the DC plug terminals and the AC plug terminals may be brass that has plasticity. Metal portions of the connecting wires are placed inside corresponding wire connecting portions and the wire connecting portions are squeezed so that the conducting wire 109 is fixed to the AC plug terminals and the DC plug terminals.

The power plug may be further provided with an end cap 108 clamped to an end of the first body 106. A communicating pore 1081 is provided on the end cap 108. An end of the second body 107 passes through the end cap 108 via the communicating pore 1081. The end cap 108 can prevent plug components disposed inside the first body 106 from falling off the first body 106 and can prevent dust and water.

Furthermore, the body 101 may be not divided into two parts including the first body 106 and the second body 107. That is, more than two mounting structures are disposed inside the body 101. The number of the mounting structures is equal to a sum of the number of the AC plug terminals and the number of the DC plug terminals. Each mounting structure may be provided with one AC plug terminal or one DC plug terminal.
